UNITED STATES PATENT OFFICE.

GILES G. BOLE, OF UNION CITY, MICHIGAN.

SIFTER-GRAVE.

1,293,677.

Specification of Letters Patent.

Patented Feb. 11, 1919.

Application filed June 6, 1918. Serial No. 238,543.

To all whom it may concern:

Be it known that I, GILES G. BOLE, a citizen of the United States, residing at Union City, in the county of Branch and State of Michigan, have invented certain new and useful Improvements in Sifter-Grates, of which the following is a specification.

This invention relates to grates, and more particularly to a sifter grate for use in connection with coal burning stoves.

One of the main objects of the invention is to provide a sifter which may be used in connection with a grate of a coal stove of standard construction, this sifter forming a supplemental grate and serving to separate the cinders from the ashes when the main grate of the stove is shaken or oscillated in the usual manner.

20 A further object is to provide a sifter, which may be readily secured to a stove grate so as to be positioned beneath the same for the purpose of receiving the ashes discharged from the stove grate when the same is oscillated or rocked, this sifter being provided with a lower detachable section so as to permit the cinders collected therein to be readily removed.

30 A further object is to provide a supplemental sifter grate of the character stated of simple construction and operation, which may be produced at small cost and may be readily applied to a stove grate of standard construction.

35 Further objects will appear from the detailed description.

In the drawings:—

Figure 1, is a top plan view of a grate constructed in accordance with my invention, 40 showing a supporting bracket therefor and the outline of a portion of a fire pot.

Fig. 2, is a side view of the same, partly in section, the bracket and outline of the fire pot being omitted.

45 Fig. 3, is a top plan view of the lower section of the sifter grate.

The stove grate "a," which may be of any suitable or standard construction is rockably supported for oscillation about a vertical axis by a bracket *b* which projects inwardly from the inner face of the fire pot "d." Mounted beneath the grate *a* is the supplemental sifter grate indicated generally by 1. This sifter grate is composed 55 of the upper section 2 and the lower section 3, which when assembled, produce a basket-

like structure disposed concentric with the stove grate and positioned beneath the same so that when the stove grate is rocked or oscillated, the ashes discharged therefrom will fall into supplemental sifter grate 1.

A plurality of bracket arms 4 are secured to the stove grate *a* by means of securing screws 5 inserted through the inner ends of the arms and projecting through the radial slots 6 in the grate, securing nuts 7 being threaded on the upper ends of the screws. As will be obvious, these arms may be readily adjusted radially of the grate *a* to accommodate a sifter grate of proper size. 70 By means of the radiating arms, the sifter grate is supported in concentric relation with the stove grate and spaced a short distance therefrom so as to permit escape of ashes and cinders from the fire pot about 75 the periphery of the stove grate *a* in the usual manner. The stove grate may be shaken or oscillated by means of a shaker handle 8 projecting therefrom in the well known manner.

Upper section 2 of the shaker grate 1 is provided, at its lower edge, with an integral ring member 9. A plurality of spaced inwardly directed securing members 10 of channel construction are secured to the under face of this ring. These channel members are of arcuate outline and conforming to the curvature of ring 9. As will be noted more clearly from Fig. 2 of the drawings, the channel members 10 are directed inwardly and coöperate with similar channel members 11 which are secured to the upper surface of an integral ring member 12 formed at the upper edge of the lower section 3 of shifter grate 1 to detachably secure the two grate sections together. It

90 will be understood, of course, that the members 9 and 10 are so spaced as to permit members 11 to be readily inserted between members 10 when the lower section 3 is 100 raised into proper relation with the upper section 2 after which the lower section 3 is turned so as to bring the channel members into proper operative relation, thus securing the lower section of the grate to 105 the upper section, while permitting it to be readily detached therefrom. To prevent accidental detachment of the lower section of the grate when the stove grate is shaken or oscillated, a double hook 13 is loosely secured at its lower end to a lug 14 formed integrally with one of the bars 15 of the

lower section, the upper eye of this hook being adapted to engage snugly over a stud 16 which projects from one of the bars 17 of the upper grate section 2. This hook 5 serves to effectually prevent accidental detachment of the lower grate section and may be readily moved out of engagement with the stud 16 so as to permit removal of this member.

10 In applying the device, the upper section 2 of the shifter grate is secured to the grate *a* of the stove in the manner previously described. After the upper section 2 of the sifter grate has been placed in proper position, the lower section 3 is detachably secured thereto and is locked against independent rotary movement by means of the hook 13 and stud 16. With the sifter grate in this position, the grate *a* of the stove 15 may be oscillated or shaken in the usual manner. The ash and cinders which are discharged from the fire pot will fall into the basketlike sifter grate, the ashes passing readily between the bars 15 and 17 20 thereof, while the cinders will be retained within the lower section 3 of this grate. After the shaking operation, the lower section 25 of the grate may be readily removed and the cinders which have accumulated 30 therein may be emptied into the fire pot of the stove, after which the lower section of the sifter grate may be readily returned to its proper position. Of course, if desired, the lower section of the sifter grate may be 35 left in position until a considerable quantity of cinders have collected therein, and it is not essential that this lower section be removed immediately after the shaking operation, as will be obvious. This sifter grate 40 may be readily applied to any stove grate or ordinary or standard construction and will be shaken or oscillated simultaneously with the shaking of the stove grate so as 45 effectually sift the ashes simultaneously with their discharge from the fire pot. While the sifter grate has been illustrated as being of circular outline, it is to be understood that

the particular shape of this grate can be readily changed to accommodate stove grates of different designs.

50

The foregoing description and the drawings have reference to what may be considered the preferred, or approved form, of my invention. It is to be understood that I may make such changes in construction and arrangement and combination of parts, materials, dimensions, etc., as may prove expedient and fall within the scope of the appended claims.

55

Having thus described my invention what 60 I claim as new and desire to secure by Letters Patent is:—

1. The combination with a stove grate of an upper sifter grate section depending therefrom, said upper section being secured 65 to the stove grate for oscillation therewith, a lower sifter grate section depending from said upper section, and detachably secured thereto, the two said sections of the sifter grate cooperating to provide a basket-like 70 structure for receiving material from above the stove grate, and means for releasably securing the lower section of the sifter grate to the upper section thereof, so as to cause oscillation of said lower section when the 75 stove grate is oscillated.

2. In combination, a stove grate mounted to have an oscillatory movement imparted thereto, a supplemental sifter grate of basket-like formation suspended from the 80 stove grate and movable therewith and comprising an upper section connected to the stove grate and a lower section, there being interengaging channel members formed with the respective sections, and means between the sections to prevent the accidental disengagement of the said interengaging channel members.

85

In testimony whereof I affix my signature in presence of two witnesses.

GILES G. BOLE.
